UNITED STATES PATENT OFFICE.

JOHN B. FREYSINGER, OF NEW BRITAIN, CONNECTICUT, ASSIGNOR TO NORTH & JUDD MANUFACTURING COMPANY, OF NEW BRITAIN, CONNECTICUT.

LATCH.

Application filed September 21, 1925. Serial No. 57,716.

This invention relates to latches for vehicle doors, and its object is to provide novel means for securing the latch-bolt in the thrown position so that the door cannot be opened from the outside until the bolt-holding means has been released. The invention also seeks to simplify the construction and thereby reduce the cost of production. These stated objects and other objects which will incidentally appear in the course of the following description are attained in such a device as is illustrated in the accompanying drawings, and the invention consists in certain novel features which will be particularly pointed out in the appended claims.

In the drawings, Figure 1 is an inside face view of a door latch embodying the invention, the bolt being secured in the thrown position;

Figure 2 is a similar view with the parts arranged to permit retraction of the bolt;

Figure 3 is a vertical section of the upper portion of the vertical spindle;

Figure 4 is a horizontal section on the line 4-4 of Figure 1;

Figure 5 is a horizontal section on the line 5-5 of Figure 1;

Figure 6 is a view similar to Figure 1 but showing a further development of the invention;

Figures 7, 8 and 9 are detail views showing different forms of detents which may be employed;

Figure 10 is a horizontal section on the line 10-10 of Figure 6.

In carrying out the invention, I employ the usual case plate 1, on which is mounted the latch-bolt 2 having its nose 3 projecting through the flange 4 of the case plate. A longitudinal slot 5 is formed in the bolt near the inner end thereof and on its upper edge is a projection 6 arranged to be engaged by the roll back 7 which is turned in the usual manner by a knob spindle and a handle (not shown) on the outer side of the door. Rotatably mounted on the case plate is a vertical spindle 8 which projects up through the edge of the door panel, and formed on or secured rigidly to this spindle near its lower end is a cam 9 which is arranged to play in the slot in the bolt. Preferably, a lug 10 is formed on the bolt at the rear end of the slot to cooperate with the cam 9 and insure retraction of the bolt when the spindle is rotated in the proper direction. To rotate the spindle, a handle 11

is provided at the upper end thereof, said handle having a hub 12 threaded on the spindle, and a collar 12^a is located below the hub 12 and receives the upper end portion of a tube or sleeve 12^b located on the spindle, said 60 collar and tube or sleeve being secured to the spindle 8 by a cross pin 13. A longitudinal groove or channel 14 is formed in the upper portion of the spindle 8 and opens through the top end of the spindle with its lower end 65 at a point just below the top edge of the door panel. Slidably mounted in the channel 14 is a rod 15 having at its lower end a laterally projecting stud 16 which passes through a slot 16^a at the lower end of the tube or sleeve 70 12^b. The upper end of the rod is equipped with a button 17 fitting slidably through the upper end of a thimble 18 which enters the hub 12 and is threaded onto the upper end of the spindle within the hub 12. Pivottally 75 mounted on the case plate adjacent the upper edge thereof and between the spindle and the flange 4 is an angle lever 19 having one arm projecting past and in proximity to the vertical spindle, the other arm of the lever extending obliquely downwardly and terminating in a fork 20 beneath the upper arm. The first-mentioned arm of the lever is formed with a cam slot 21 near its free inner end which is engaged by the stud 16, and at its end 80 the lever arm is constructed to be engaged by the upper free end of a spring detent 23 which is secured upon the case plate below the lever arm. Pivottally mounted upon the case plate at a point between the roll-back and the operating angle lever 19 is a locking lever or dog 24 having one end fitted in the fork 20 with a rolling sliding engagement and its opposite end arranged to abut the roll-back and thereby prevent movement of the same. 85

Normally, the parts are in the positions shown in Fig. 2 and the bolt 2 may be retracted by manipulation of the outside knob or the spindle 8, the detent 23 holding the dog 24 and its setting lever 19 in the positions shown. The rod 15 at this time slides freely in the groove 13, as the spindle is turned, by reason of the engagement of the stud 16 with the obliquely disposed walls of the slot 21 and the lever 19 and dog 24 remain at rest. 90 If the door is to be locked against outside opening, pressure is exerted on the button or cap 17 to push the rod 15 downward and this action rocks the lever 19 into the position shown in Fig. 1, inasmuch as the stud 16 is at 105 110

the higher end of the slot 21 and the spindle 8 is at this time held against turning. The dog 24 is, consequently, swung against the roll back 7 and the knob spindle rendered 5 inoperative. Now, when the occupant of the car desires to permit the door to be opened from the outside, he merely turns the handle 11 and the spindle 8 in the direction to retract the bolt. This movement causes the stud 16 10 to ride against the upper wall of the slot 21 and, as the stud at this time is at the lowest limit of its movement, the force of the detent 23 is overcome and the lever 19 rocked back to the position shown in Fig. 2 restoring 15 the normal condition. If the handle 11 be now released, the spring 37 returns it to the position shown in Fig. 2 and projects the bolt,—the pin 16 riding through the slot 21 while the lever 19 is held by the detent 23.

20 In Figures 1 and 7, the detent 23 is shown as having its free end formed into a transverse tooth or ridge 22 adapted to engage either one of two grooves or recesses 25 in the side of the lever to thereby yieldably hold the lever set. In Figures 6 and 8, the free end of the detent 25^a is flat and bears upon a ball or roller 26 fitted within an opening in the end of the lever 27 to ride on the case plate 100 as the lever rocks and engage 30 one or another pocket 28 in the case plate. In Figure 9, the lever 29 has a seat for the ball 30 which does not ride on the case plate but rides between the pockets 31 on the detent 32 and engages either of said pockets. In 35 all three forms, the detent operates automatically to hold the operating lever against accidental movement.

40 My lock is simple, inexpensive and efficient. It will be understood that the lock thus described is intended more particularly for closed cars in which one door is key-controlled and the other doors are locked from the inside.

45 It is, of course, desirable to provide the lock on one door in such form that it may be unlocked from the outside, and a form answering this requirement is illustrated in Figure 6 which also shows some structural refinement. In this form of the invention, tongues are struck up from the case plate 100 and rolled toward each other to form bearings 33 for the vertical spindle. The flange 101 of the case plate has a lip 102 struck therefrom to aid in supporting and guiding the bolt 34 and the latter is actuated in one direction by a cam 35 on the vertical spindle 8. A volute spring 37 is secured at its inner end to a stud on the case plate and has its opposite free end bearing against the inner end of the bolt, tending constantly to project the same, and it is to be understood that in actual practice an equivalent spring acts upon the bolt 2. The operating lever 47 is 55 operatively connected with the spindle 36

in the same manner as the lever 19 is connected with the spindle 8 and controlled by a push button 370 at the top of the spindle, and the roll back 38 and horn or projection 39 are essentially the same as the elements 70 7 and 6 respectively in the first-described lock. Instead of the bent locking lever, 24, however, there is provided a substantially triangular locking plate 40 pivoted upon the case plate at a point near the spindle 36 75 and provided on its side with a stud 41 engaged by the fork 42 of the lever 47. The forward edge of the locking plate is properly shaped to abut the roll-back immediately 80 over the horn 39 when rocked by the operating lever, and it is further provided with a notch 43 receiving a lug or cam 44 of a cylinder lock indicated conventionally at 45. When the barrel or cylinder of the lock 45 is 85 rolled, the lug 44 engaged with the notch 43 will rock the locking plate 40 so that movement of the bolt 34 will be permitted or prevented, as desired. The cylinder lock is mounted near a corner of the face plate and 90 extends through the door.

Having fully described my invention what I claim as new and desire to secure by Letters-Patent, is:—

1. In a door latch, the combination of a 95 latch-bolt, a vertical rotatable spindle for moving the bolt, a roll-back by which the bolt may be moved, a locking element having one end arranged to abut the roll-back whereby to prevent movement thereof, an operating angle lever provided with a fork at one end having sliding engagement with the locking element, and means carried by the spindle and engaged with the opposite end of the operating lever to set the same.

2. In a door latch, the combination of a 105 latch-bolt, a vertical spindle for moving the bolt, a roll-back by which the bolt may be moved, a locking element arranged to abut the roll-back and prevent movement thereof, an operating lever engaged at one end with 110 the locking element and having a cam slot near its opposite end, and a stud slidably mounted on the spindle and engaged in the cam slot whereby to set the lever.

3. In a door latch, the combination of a 115 latch-bolt, a vertical spindle for moving the bolt, a roll-back by which the bolt may be moved, a locking element arranged to abut the roll-back and prevent movement of the same, an operating lever engaged at one end with the locking element and provided near its opposite end with a cam slot, a detent 120 yieldably engaging said end of the operating lever, and a stud slidably mounted on the spindle and engaged in said cam slot whereby to set the lever.

4. In a door latch, the combination of a 130 latch-bolt, a vertical spindle for moving the bolt, said spindle having a longitudinal channel in its upper portion, a roll-back by which

the bolt may be moved, means for locking the roll-back including a lever having a cam slot in one end, a rod slidably mounted in the channel in the spindle and provided at its lower end with a stud playing in said cam slot, and means at the upper end of the rod to depress the same and set the lever.

5. In a door latch, the combination of a latch-bolt, a vertical rotatable spindle for moving the bolt, a roll-back by which the bolt may be moved, a locking element arranged to abut the roll-back and prevent movement thereof, an operating lever operatively engaged with the locking element, means carried by the spindle for setting the operating lever, and means independent of

the operating lever for setting the locking element.

6. In a door latch, the combination of a latch-bolt, a vertical rotatable spindle for moving the bolt, a roll-back by which the bolt may be moved, a locking element arranged to abut the roll-back and prevent movement thereof, an operating lever operatively engaged with the locking element, means carried by the spindle for setting the operating lever, an externally operable lock, and a cam carried by said lock and operatively engaged with the locking element.

In testimony whereof, I have signed this specification.

JOHN B. FREYSINGER.
